PENCIL MARKING POINT

Benjamin Solow, Philadelphia, Pa.
(5743 Rhodes Ave., North Hollywood, Calif.)

Filed May 17, 1955, Ser. No. 508,957

2 Claims. (Cl. 120—83)

This invention relates to novel pencil marking-points and to a method and apparatus for making such marking-points.

For many years pencil manufacturers have sought a mechanical lead pencil that would provide a sharp point, which sharp point would not be dulled after the initial writing period.

A suggested solution to this problem is the magazine form of mechanical pencil, namely pencils in which a series of sharp points are contained in a magazine, and in which means are provided for ejecting worn points and substituting new ones therefor. A number of United States patents have been granted on such devices, such as Fornander Patent 499,191, issued June 6, 1893; Goldsmith Patent 618,172, issued January 24, 1899, etc.

However, the magazine pencil has never proven commercially practicable. The salient reason for the failure of this pencil lies in the fact that it has not been possible to provide a sharpened pencil lead having adequate structural strength. Thus, the pencil leads are subjected to stresses and strains in manufacture and assembly, particularly during the magazine loading operation, in transport, and while positioned within the pencil, etc. causing the points to shatter, split, or become dull. As it has not heretofore been possible to provide a pencil marking-point having adequate strength, the magazine form of pencil has not been commercially exploited.

This invention has as an object the provision of a pencil marking-point for use in a magazine pencil, which marking-point possesses great structural strength.

A further object of the present invention is the provision of a method of manufacturing pencil marking-points possessing great structural strength.

Another object of the present invention is the provision of apparatus for making pencil marking-points of great strength.

Still further objects will appear hereafter.

For the purpose of illustrating the invention there are shown in the drawings forms which are presently preferred; it being understood, however, that this invention is not limited to the present arrangements and instrumentalities shown.

Referring to the drawings, wherein like reference characters refer to like parts.

Figure 1 is a perspective view of one embodiment of the pencil marking-point of the present invention.

Figure 2 is a part elevation and part longitudinal sectional view of a split tube magazine of the present invention showing a plurality of pencil marking-points nested together.

Figure 3 is a fragmentary enlarged sectional view of a portion of Figure 2 showing the relationship of the pencil marking points nested together.

Figure 3a is a vertical sectional view of a modified embodiment of the pencil marking-point of the present invention.

Figure 4 is a perspective view of an embodiment of a

2

mold for forming the pencil marking points of the present invention.

Figure 5 is a longitudinal sectional view of the sheet metal plate used to form the support collar for the pencil marking-points of the present invention.

Figure 6 is a fragmentary sectional view through the sections of the mold with the mold sections in operative alignment, and with a pencil marking-point formed therebetween.

10 Figure 7 is a diagrammatic sectional view of the punching-out stage in the manufacture of the pencil marking-points of the present invention.

Referring to the drawings, and initially to Figures 1, 2 and 3 the pencil marking-point of the present invention

15 is designated 10. Marking-point 10 comprises a sheet metal tubular collar 12 and a pencil lead 14. Pencil lead 14 has a sharp conical point 16 surrounded by an annular flat 17 at one end, and a cone-shaped cavity 18 at the other end, surrounded by an annular flat 19.

20 The tubular collar 12 has an inwardly directed flange 21 which covers a portion of flat 17. The cone-shaped cavity 18 is of a size sufficient to form a nest for the tip portion of the point 16 of a similarly shaped pencil lead 14 so that internesting or sheathing of a plurality of pencil points may be accomplished in vertical alignment

25 within a split tube magazine 23 (see Figures 2 and 3). As seen particularly in Figure 3, when the marking-points are internested, flange 21 of each upper marking point rests on the annular upper edge 24 of the metal collar 12 of the next lower marking-point. There is a gap between point 16 of each upper marking-point and cavity 18 of each lower marking-point. In this manner

30 all longitudinal thrust is borne by the metal collar 12 and not by lead 14 when the marking points are inter-

35 nested.

The metal tubular collar 12 serves as a shield protecting pencil lead 14 from shock, when the marking-point 10 is grasped at its side within the magazine 23. The inter-

nesting of point 16 of the pencil lead 14 of one marking-

40 point 10 within the cone-shaped cavity 18 of the pencil lead 14 of another marking-point 10 leads to further structural strength as the points 16 are protected by the pencil lead 14 and metal tubular collar 12 of the marking-point within which the point 16 is received.

45 The method and apparatus for manufacturing the pencil marking-points of the present invention can be ascertained from an examination of Figures 4 through 7, wherein the manufacture of the pencil marking-point 10 is illustrated.

50 One embodiment of the mold used in the present invention is diagrammatically illustrated in Figure 4. The mold designated generally as 50 comprises an upper or cap section 52 and a lower or bottom section 54. The sections 52 and 54 are provided with respective mating

55 conical knobs and cavities, so that when upper section 52 alignedly rests on the upper surface of lower section 54, each cavity 53 formed in lower section 54 receives a mating conical knob 55 of upper section 52.

The cavity 53 in lower section 54 includes a down-

60 wardly directed cone-shaped recess 56 which forms the sharp conical point 16 of pencil lead 14, and a surrounding or contiguous plateau 57 on which flange 21 rests. Conical knob 55 is smaller than the mouth of cavity 53 in lower section 54 and forms cone-shaped cavity 18 in pencil lead 14. Surrounding conical knob 55 is a raised contiguous plateau 59 which forms flat 19 in pencil lead 14.

65 A sheet metal plate 60 of thin sheet metal (see in particular, Figure 5) having annular flanges 62, which serves as a metallic liner (see Figure 6) is fitted over bottom section 54. As shown in Figure 6, plate 60 covers the

surface of bottom section 54, except for the cone-shaped recesses 56 and the plateaus 57.

The conventional components used in forming pencil leads, such as a plasticized mass of finely divided graphite, soot and clay are placed in the space between the depending annular flange 62 and the cone-shaped recess 56 in each of the cavities 53 of bottom section 54. Sufficient pencil lead component composition is included so that when mold section 52 is placed over mold section 54, the pencil lead components fill the cavity intermediate upper section 52 and lower section 54.

No claim is made to novel pencil lead compositions. Accordingly, conventional pencil lead compositions may be used. Straight Patent 2,388,447; Ferst Patent 2,355,-639; Van Dusen Patent 2,566,753; Loy Patent 2,645,582; Maneval Patent 2,679,460 and Loy Patent 2,682,476 disclose various pencil lead compositions. The plasticized pencil lead composition shaped in the aforesaid manner may be dried within the mold and then fired at conventionally used firing conditions.

When the temperature of the mold has been returned to room temperature, upper section 52 is raised from lower section 54 and plate 60 carrying the hardened pencil marking-points is removed from lower section 54.

The plate is then positioned on a suitable multipunch press 70 having a plurality of punches 72 (see Figure 7).

As shown in Figure 7 the pencil marking-points of the present invention are cut away from plate 60 on the downward movement of punch 72 (see top arrow in Figure 7). The cut-away pencil marking-points 10 fall downwardly in the direction of the bottom arrow, and are collected at the bottom of the press 70.

Preferably, the split tube magazine 23 is positioned immediately below the openings in multipunch press 70 so that the movement of punch 72 pushes the cut-away pencil marking-points directly into the split tube magazine 23.

In the embodiment shown in Fig. 3a, the pencil marking-point includes a collar 12a and a pencil lead 14a. Collar 12a is crimped somewhat at 15, so that it partially projects into pencil lead 14a. The inward projection 15 of collar 12a serves as a thrust pillow and retention stop absorbing longitudinally directed stresses.

Pencil lead 14a is provided with a point 16a, and a cone-shaped cavity 18a surrounded by an annular flat 19a. The lower end of collar 12a is provided with an inwardly directed flange 21a.

The present invention may be embodied in other specific forms without departing from the spirit or essential attributes thereof, and, accordingly, reference should be made to the appended claims, rather than to the foregoing specification as indicating the scope of the invention.

Having thus described my invention I claim:

1. A pencil marking-point including a pencil lead consisting of a writing material having a generally cylindrical body portion, a conically tapered point at one end of said pencil lead, a cone-shaped cavity at the other end of said pencil lead, with the apex of said cone-shaped cavity disposed on the longitudinal axis of the pencil lead, the walls of said cavity conforming to the outer shape of the conically tapered point, whereby a conically tapered point of a similarly formed pencil lead may be nested therein, an open-ended tubular imperforate metal collar circumferentially embracing the body portion of the pencil lead, with said conically tapered point of the pencil lead projecting through one open end of said collar, and with said one end of the collar having a radially inwardly

directed flange covering a portion of the pencil lead contiguous to said conically tapered pencil lead point, with the portion of said pencil lead point intermediate said flange and the tip of the pencil lead comprising the conically tapered point, and with said conically tapered point projecting through and beyond said one end of said collar, and with the other end of the collar adjacent to the cone-shaped cavity in the pencil lead extending a spaced distance beyond the end of the pencil lead which has the cone-shaped cavity, whereby a plurality of marking-points may be arranged tandemwise with the conically tapered point of one being received within the cone-shaped cavity of the other, and with the sole engagement between such marking-points being the metal to metal contact of the radially inwardly directed flange of one to the other end of the collar of the other so that thrust on the pencil lead is avoided.

2. A pencil marking-point assembly including a tubular magazine, and a plurality of similar pencil marking-points arranged therewithin tandemwise and in the same direction, each pencil marking-point including a pencil lead consisting of a writing material having a generally cylindrical body portion, a conically tapered point at one end of said pencil lead, a cone-shaped cavity at the other end of said pencil lead, with the apex of said cone-shaped cavity disposed on the longitudinal axis of the pencil lead, the walls of said cavity conforming to the outer shape of the conically tapered point, an open-ended tubular imperforate metal collar circumferentially embracing the body portion of the pencil lead, said conically tapered point of the pencil lead projecting through one open end of said collar, the other end of said collar extending beyond the end of said pencil lead having said cone-shaped cavity, a radially inwardly directed flange covering a portion of the lead contiguous to said conically tapered point, with the portion of said pencil lead point intermediate said flange and the tip of the pencil lead comprising the conically tapered point, the other end of the collar extending beyond the end of said pencil lead having said cone-shaped cavity, with the tip of the conically tapered point of the pencil lead of one marking-point nested within the cone-shaped cavity of the pencil lead of another marking-point, and with the radially inwardly directed flange of the former marking-point operatively engaging the outwardly extending end of the collar of the latter marking-point, whereby the pencil lead portion of each of said marking-points is spaced from the pencil lead portion of each adjacent marking-point.
